UNITED STATES PATENT OFFICE.

JUSTIN K. ANDERSON AND GEORGE E. TAYLOR, OF CHARLESTON, WEST VIRGINIA.

GUIDE FOR TYPEWRITTEN SHEETS.

Application filed September 25, 1923. Serial No. 664,742.

To all whom it may concern:

Be it known that we, JUSTIN K. ANDERSON and GEORGE E. TAYLOR, citizens of the United States, residing at Charleston, in the county of Kanawha and State of West Virginia, have invented certain new and useful Improvements in Guides for Type-written Sheets, of which the following is a specification.

- 10 This invention relates to the preparation of printed and typewritten sheets, such as letters and reports and in general provides novel guide means whereby the printed or typewritten matter can be readily and conveniently located upon the sheet within desirable limits.
- 15 It is the further object of this invention to provide guide means of particular advantage in preparing lengthy reports to be typed with as many extra copies as possible and wherein it is desired that all the pages or copies, when typed, shall present a suitable margin on the left side for binding, and on the top, bottom and right side to present
- 20 a uniform and pleasing appearance.

In addition to being susceptible of the uses and advantages above set forth, this invention is also adapted for use with all kinds of typewritten letters; reports; tabulations of figures; ruling of columns and spacings, and likewise with any form of typewriting or similar methods of writing or printing.

With the foregoing in view, this invention consists in the provision of guides adapted to be associated with the sheet to be typed as to visibly define the limits of the space within which it is desired to confine the typed matter, and which thus acts as a guide to the typist so that the typewriting machine may be operated accordingly.

In the accompanying drawing illustrating this invention—

Fig. 1 is a view of a thin sheet of paper with a border defined thereon;

Fig. 2 is a view of a piece of commercial carbon paper with a border defined thereon;

Fig. 3 is a view of a modification of this invention in which the guide sheet is provided with interior rulings and spacings.

Although the invention is obviously ca-

pable of a wide and varied range of application it shall for the present purpose be described only with reference to its particular use as a guide to a typist in typing multiple copies, for which purpose it is desirable that the guiding means be of such a nature as to readily catch the eye of the typist when the limit of the typing space is approached although presenting no distraction to the typist otherwise. This is accomplished in the first instance as shown in Fig. 1, by ruling border lines 10 on a sheet 11 of thin paper which is adapted to be placed beneath the first of the multiple sheets or copies to be typed, and on top of the first sheet of carbon paper, in which position of the papers the border lines 10 will be visible through the first sheet to act as a guide to the typist.

As illustrated in Fig. 2 border lines 12 may be marked on the back of a sheet of carbon paper 13 the lines 12 preferably being of red or other contrasting color to add to the visibility of the same through the first or top sheet of paper.

In Fig. 3 there is shown a guide means, preferably a sheet of carbon paper 15 having a plurality of horizontal rulings 16 and vertical rulings 17 on the reverse side thereof. These rulings 16 and 17 are of contrasting color to add to the visibility thereof through the first sheet when the carbon paper is in use. This type of guide means is adapted for all kinds of tabulations and statements.

Having thus described the invention what is claimed is—

1. A guide for locating typing or printing on a sheet so as to leave suitable margins, consisting in a guide sheet having a border of a color contrasting with the body of the guide sheet serving to determine the limits of space for typing or printing on said first sheet.

2. A guide for locating typewritten or printed matter on a sheet to define a border thereon, consisting of a sheet of carbon paper having the reverse side ruled to provide a border serving to define the limits of space within which the said typewritten or printed matter is to be confined, when said

carbon paper is placed beneath and in contact with said first sheet.

3. A guide for locating typewritten or printed matter on a sheet including a sheet

5 of carbon paper having a plurality of horizontal and vertical guide lines ruled thereon to be visible through the first sheet when

the carbon paper is placed beneath and in contact with said first sheet.

In testimony whereof we affix our signatures. 10

JUSTIN K. ANDERSON.
GEORGE E. TAYLOR.
